US0D1070843S

(12) **United States Design Patent** (10) **Patent No.:** **US D1,070,843 S**
(45) **Date of Patent:** **** Apr. 15, 2025**

(54) **ELECTRONIC DISPLAY ASSEMBLY**

(71) Applicant: **Manufacturing Resources International, Inc.**, Alpharetta, GA (US)

(72) Inventors: **William Dunn**, Alpharetta, GA (US); **Mike Brown**, Cumming, GA (US)

(73) Assignee: **Manufacturing Resources International, Inc.**, Alpharetta, GA (US)

(**) Term: **15 Years**

(21) Appl. No.: **29/897,628**

(22) Filed: **Jul. 17, 2023**

(51) LOC (15) Cl. **14-02**

(52) U.S. Cl.

USPC **D14/307**

(58) **Field of Classification Search**

USPC D14/302-307, 900-902; D13/163; D20/10; D21/332, 325, 369, 370; D99/28; D6/397, 466; 194/206; 361/679.01, 679.02, 679.04, 679.21, 361/679.57, 725

(57) **CLAIM**

The ornamental design for an electronic display assembly, as shown and described.

DESCRIPTION

FIG. 1 is a front perspective view of the electronic display assembly;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and,

FIG. 7 is a bottom view thereof.

The broken lines illustrate unclaimed portions of the electronic display assembly.

1 Claim, 5 Drawing Sheets
